UNITED STATES PATENT OFFICE

2,688,903

SHAPER ATTACHMENT FOR LATHES

Harve L. Hager, Oakland, Calif.

Application October 27, 1952, Serial No. 317,047

3 Claims. (Cl. 90—40)

1

The present invention relates to a shaper attachment for a lathe by means of which work normally done on a shaper or milling machine may be performed on a lathe. Thus the attachment is adapted to be utilized on household lathes and in small plants, where regular shapers would be prohibitive. It consists of the combinations, constructions, and arrangement of parts, as hereinafter described and claimed.

An object of my invention is to provide a reciprocating ram having a tool-carrying clapper box mounted thereon, the ram being made for attachment to a lathe bed and being adapted to be moved back and forth by a wobble plate, the latter being actuated by a rotating spindle of the headstock forming part of the lathe. Accordingly, the structure thus provided will permit shaper operations to be accomplished on the lathe.

Moreover, and as a further object, it is proposed to provide a shaper attachment for a lathe, which is subject to a wide variety of adjustments, thus permitting various operations to be performed.

Another object of this invention is to provide an attachment of the character described that is simple in construction, durable and efficient for the purpose intended.

Other objects and advantages will appear as the specification proceeds, and the novel features will be set forth in the claims hereunto appended.

Drawings

For a better understanding of the invention, reference should be had to the accompanying drawings, in which:

Figure 1 is a front elevational view of a conventional lathe having my attachment secured thereto;

Figure 2 is an enlarged transverse sectional view taken along the vertical plane II—II of Figure 1;

Figure 3 is an elevational view of my attachment on a larger scale than in Figure 1, parts being shown in section;

Figure 4 is a horizontal sectional view taken through the wobble plate, along the line IV—IV of Figure 3;

Figure 5 is a transverse sectional view taken along the vertical plane V—V of Figure 3, illustrating the reciprocating ram and its guide support;

Figure 6 is a top plan view of Figure 3;

Figure 7 is a fragmentary view disclosing the

2

wobble plate adjusted into angular position relative to the axis of the headstock spindle;

Figure 8 is a perspective view of a spring fork for yieldingly holding the clapper box in its normal position;

Figure 9 is a vertical transverse sectional view taken along the line IX—IX of Figure 3, disclosing the arrangement for clamping the ram-guiding support to the lathe bed;

Figure 10 is a front elevational view of the clapper box during the return stroke;

Figure 11 is a transverse sectional view taken along the vertical plane XI—XI of Figure 3, showing the vise holding a workpiece in operative relation with respect to the tool carried by the clapper box; and

Figure 12 is an end elevational view of the clapper box adjusted into angular position so that its tool will cut inclined surfaces.

While I have shown only the preferred form of my invention, it should be understood that various changes, or modifications, may be made within the scope of the annexed claims without departing from the spirit thereof.

Detailed description

For the purpose of illustration, I have shown a conventional lathe indicated generally at A having parallel ways 10—10 extending lengthwise thereof, and along which an adjustable carriage B is movable. The headstock and tailstock are designated at C and D, respectively. Upon this carriage there is mounted the cross-feed E in the ordinary manner. Within the headstock the usual tubular spindle F is journaled for rotation, this spindle being turned by a drive mechanism accommodated in a housing 11 (see Figures 1 and 3).

With this background in mind, I make use of a tapered shank G, which is insertable into the spindle F so as to be rotated by the latter. This shank has a spherical head 12 at its outer end, and the head is fashioned with a slot 14 to receive an eye-bolt 15 (see Figures 1, 3 and 4). It will be noted that this eye-bolt is pivotally secured by a transverse pin 16 to the spherical head of the shank. The outer ends of this pin are slidably received in arcuate grooves 17—17 fashioned in an inner race 18 of a wobble plate H surrounding the head 12. Moreover, a washer 19 and nut 20 are mounted on the eye-bolt and hold the inner race 18 in place. An outer race 21 is mounted around the inner race 18, with a ball bearing 22 arranged therebetween.

Referring to Figures 2 and 6, it will be ob-

served that the inner race 18 rotates with the tapered shank G, while the outer race 21 is held against rotation by an arm 23 fixed to and projecting therefrom. This arm is connected by a ball joint 24 to the upper end of a holding link 25, and the latter has its lower end secured by a universal joint 26 and clamp 27 to one of the ways 10. However, the link 25 permits the wobble plate H to swing into various angular positions about the transverse pin 16, as will be apparent by comparing Figures 3 and 7.

Now the outer race 21 of the wobble plate has a bracket 28 fixed to the top thereof to which a pitman 29 is attached by a universal joint 30. In turn, the pitman is coupled by a ball joint 31 to a reciprocating ram J, which is slidably mounted for back and forth movement in a guide support 32 mounted on an adjustable standard 33.

In reality the ram J includes a horizontally-disposed slide 34 to which a bracket 35 is adjustably secured, the ball joint 31 being fastened to this bracket. For permitting the slide 34 to be extended or retracted relative to the bracket 35, the former is provided with clamping studs 36 that pass through slots 37 fashioned in the sides of the latter.

Reference is made to Figures 1, 3, 6 and 9, wherein it will be apparent that the lower end of the standard 33 has a base 38 arranged to overlie portions of the lathe bed ways 10-10 so as to be adjustable therealong. This base coacts with a clamping bar 39, which underlies portion of these ways as shown in Figure 9. Studs 40 are provided for drawing the bar 39 toward the base 38 to thereby clamp the standard 33 in adjusted position.

As shown in the drawings, the workpiece K to be cut by my shaper attachment is supported in a vise L mounted on the cross-feed E, with this workpiece being arranged beneath a clapper box M, which is pivoted by a pin 41 to the forward end of the reciprocating ram J.

This clapper box is standard in construction, and includes a vertically-adjustable rod 42 having a cutting tool 43 mounted on the lower part thereof. Also, the clapper box may be swung into angular positions relative to the ram J, as suggested in Figure 12, and locked in these positions by a stud 44, thereby permitting inclined surfaces 45 to be cut by the tool.

At the top of the rod 42 there is provided an adjusting nut 46 having an annular groove 47 formed therein to receive the fingers 48 of a bifurcated fork N (see Figures 6 and 8). The reciprocating ram J, when moving to the right in Figure 3, will cause the tool 43 to cut material from the workpiece K. On return stroke of the pitman 29 and the ram, the clapper box will swing about its pivot 41 against the action of a spring 49 interposed between the fork N and a lug 50 provided on an upstanding portion of the ram slide 34. When the ram starts a forward stroke, this spring will return the clapper box to its normal upright position, thus restoring the tool 43 to its cutting engagement with the workpiece.

In operation, the wobble plate H may be adjusted so as to furnish the desired stroke to the pitman 29 and its ram J during rotation of the shank G. This adjustment is obtained by anchoring a head 51 to the shank with a pin 52, and then providing a threaded stud 53 on this head having a presser shoe 54 bearing against the rear face of the wobble plate. Adjustment of the stud 53 will result in swinging the wobble plate into angular positions relative to the longi-

tudinal axis of the shank G, thereby varying the stroke of the ram.

Summary

5 The assembling and operation of my shaper attachment for a lathe are summarized briefly as follows:

Initially the shank G is inserted into and anchored to the tubular spindle F of the headstock C, and the standard 33 is secured upon the ways 10-10 of the lathe bed by the clamping bar 39. Furthermore, the stud 53 is adjusted so as to impart the desired stroke to the pitman 29 and the reciprocating ram J when the wobble plate H 15 is turned by the rotating shank G. Also, the slide 34 and bracket 35 may be adjusted relative to one another.

Next, the workpiece K is clamped in the vise L, and the clapper box M adjusted so that its tool 43 will cut material from the workpiece to the desired depth. In the event that inclined surfaces 45 are to be cut, as suggested in Figure 12, the clapper box is adjusted into the necessary slanting position.

20 As the wobble plate H is rotated, the pitman 29 will cause the ram J to be reciprocated back and forth in the guide support 32, with the tool 43 cutting on its forward strokes and dragging lightly back over the workpiece on the return strokes. As the cutting progresses, the cross-feed E may be moved to bring new surfaces of the workpiece beneath the cutting tool.

25 Thus my attachment will permit a lathe to be employed for performing the operations of a shaper, all with a relatively simple mechanism.

30 It will be noted from the plan view shown in Figure 6 that the carriage B is substantially H-shaped, and that the ram support 33 and its base 38 are nested in one of the recesses of this carriage for better work and tool positioning.

I claim:

1. In a shaper attachment for a lathe: a shank adapted to be secured to a rotatable spindle in the headstock of a lathe; a wobble plate including an inner race pivotally attached to the shank to turn therewith, and an outer race surrounding the inner race; means for adjusting the wobble plate into angular inclined positions relative to the axis of the shank; means for retaining the outer race against rotating about said axis; a pitman attached to the outer race of the wobble plate so as to be reciprocated back and forth when the wobble plate occupies an inclined position with respect to the shank; a ram 45 connected to the pitman for reciprocation by the latter; a guide support adapted to be secured to the lathe, and having the ram mounted therein for back and forth movement; a clapper box carried by the ram, and having a cutting tool carried thereby; and means for adjusting the guide support longitudinally of the lathe.

2. In a shaper attachment for a lathe: a shank adapted to be secured to a rotatable spindle in the headstock of a lathe; a wobble plate including an inner race pivotally attached to the shank to turn therewith, and an outer race surrounding the inner race; means for adjusting the wobble plate into angular inclined positions relative to the axis of the shank; means for retaining the outer race against rotating about said axis; a pitman attached to the outer race of the wobble plate so as to be reciprocated back and forth when the wobble plate occupies an inclined position with respect to the shank; a ram having a bracket connected to the pitman for reciproca-

tion by the latter; the ram further having a slide adjustably secured to this bracket so as to be extendible or retractable relative to the bracket; a guide support adapted to be secured to the lathe, and having the ram slide mounted therein for back and forth movement; and a clapper box carried by the slide of the ram, and having a cutting tool carried thereby.

3. In a shaper attachment for a lathe: a shank adapted to be secured to a rotatable spindle in the headstock of a lathe; a wobble plate including an inner race pivotally attached to the shank to turn therewith, and an outer race surrounding the inner race; means for adjusting the wobble plate into angular inclined positions relative to the axis of the shank; an arm fixed to the outer race to project therefrom; a link having one end thereof universally connected to this arm, and its other end universally attached to a clamp; the latter being made for clamping upon a way

of the lathe; a pitman attached to the outer race of the wobble plate so as to be reciprocated back and forth when the wobble plate occupies an inclined position with respect to the shank; a ram connected to the pitman for reciprocation by the latter; a guide support adapted to be secured to the lathe, and having the ram mounted therein for back and forth movement; and a clapper box carried by the ram, and having a cutting tool carried thereby.
